UNITED STATES PATENT OFFICE.

EDWARD CRAIG, OF ST. JOSEPH, MICHIGAN, ASSIGNEE TO SARANAC MACHINE CO., OF ST. JOSEPH, MICHIGAN, A CORPORATION OF MICHIGAN.

MULTIPLE-HEAD STAPLER-MACHINE.

1,192,392.

Specification of Letters Patent. Patented July 25, 1916.

Application filed August 5, 1910. Serial No. 575,642.

To all whom it may concern:

Be it known that I, EDWARD CRAIG, a citizen of the United States of America, and resident of St. Joseph, Berrien county, Michigan, have invented a certain new and useful Improvement in Multiple-Head Stapler-Machines, of which the following is a specification.

My invention relates to machinery for making boxes or other similar articles.

It relates more particularly to machinery for stapling together the different parts of a box or carton, for example, the ordinary pasteboard carton, or boxes made of thin material like wood veneer.

Generally stated, the object of my invention is to provide a stapling machine that will drive in one operation all the staples which are necessary to hold the box or carton together.

Special objects are to provide an improved construction whereby a plurality of stapling heads may be arranged close together in a row, whereby a row of staples may be driven to hold the box or carton together, by one simultaneous operation of all the stapling heads, the latter being accessible from three sides of the machine, thus permitting the box or carton to be inserted readily under the stapling heads, the said row of stapling heads being provided with a standard or support only at one end thereof, thus leaving the other end of the said row unsupported.

Another object is to provide a stapling machine in which a plurality of stapling heads are arranged in a row above a table, and in which the anvil upon which the staples are clenched consists of a long swinging bar which extends below the row of stapling heads, and which is adapted to enter the box or carton while the latter is in a flattened or collapsed condition, thus affording a long support upon which the staples are clenched, the length of said bar being sufficient to enable it to receive and clench all the staples which, when driven, extend in a row longitudinally of the upper surface of said bar, as will hereinafter more fully appear.

Another object is to provide an improved construction whereby a large number of staples may be disposed in a row and arranged close together, each stapler being arranged in such position that the staples are all

driven obliquely to a line extending parallel with the said row, notwithstanding that the cams by which the staplers are actuated are all mounted upon a shaft which extends above the row of staplers, as will hereinafter more fully appear.

It is also an object, of course, to provide certain details and combinations and features of improvement tending to increase the general efficiency of a machine of this particular character.

To the foregoing and other useful ends, my invention consists in the matters herein-after set forth and claimed.

In the accompanying drawings, Figure 1 is a side elevation of a stapling machine or box-making machine embodying the principles of my invention; Fig. 2 is a front elevation of the machine shown in Fig. 1; Fig. 3 is a plan of the machine shown in Figs. 1 and 2; Fig. 4 is a perspective of the box or carton upon which the said machine is adapted to operate by inserting a row of staples along one corner thereof to secure the parts together; Fig. 5 is an enlarged section on line 5—5 in Fig. 3; Fig. 6 is an enlarged cross-section of the mandrel or clench bar which is adapted to be inserted in the box or carton, as shown in Fig. 5, and which serves as an anvil for clenching the staples; Fig. 7 is a horizontal section on line 7—7 in Fig. 5; Fig. 8 is an enlarged detail view of the ratchet mechanism for operating the feed shaft; Fig. 9 is an enlarged vertical section through the forming and driving elements of one of the staplers, said section being taken on line 9—9 in Fig. 7; Fig. 10 is an enlarged detail section on line 10—10 in Fig. 7; and Fig. 11 is a horizontal section on line 11—11 in Fig. 10.

As thus illustrated, my invention comprises the base A, which is cast integral with the upright post or standard B. A table C has one end thereof supported upon the standard B, and is adapted to slide up and down upon the latter, being controlled by a vertically disposed hand screw c, which latter serves also as a post or support for receiving the pressure of the work upon the table. A wide bar D has one end thereof rigidly secured to the top of the post or standard B, and is arranged with one edge upward and the other edge downward, whereby it is adapted to support a considerable weight, the strain being crosswise.

thereof. At the top of the post B there is a bearing b , and a similar bearing b' is supported on the outer end of the bar D, the two bearings being held in alignment. A driving shaft E is supported in said bearings and provided with the circular eccentric cams e, which cams are disposed as close together as possible, but with sufficient space between them to accommodate the connecting members or tie bars e' by which the said shaft is tied to the bar D. In other words, the upper end of each bar e' is in the nature of a bearing for the shaft, so that the latter cannot sag or spring between its ends. Moreover, it will be seen that this method of tying the shaft and bar D serves to make a very strong and rigid structure, and one which will stand considerable strain without being sprung or broken, notwithstanding that it is only supported at one end,—that is to say, at the end where the shaft and the bar D are supported by the post B, their outer ends being entirely unsupported. The stapler heads F are arranged in a row along the lower edge of the bar D, and are rigid with the bars e', with the exception, of course, of the operative parts thereof, such as the usual staple former, driver and loop bar, which are shown in Fig. 9, and which, being so common and well known, do not require any detailed description. In other words, the said stapler heads may be of any suitable known or approved construction, so far as the devices for forming and driving the staples are concerned. It is essential, however, in order to accomplish the desired results, that the said stapling heads be disposed obliquely to the bar D, as shown more clearly in Fig. 7, whereby the staples are driven in a row, but each staple extends crosswise and obliquely to the line of said row (see Fig. 4). Furthermore, each staple driver f is secured to a vertically reciprocating bar f' that constitutes a part of the driver and slides up and down in the channel E' of the adjacent bar e', as shown more clearly in Fig. 5. The upper end of this bar f' has a roller f'' that engages in the circular track or way of the cam e, whereby the staple driver is reciprocated up and down to drive the staples. The staple former F' is, moreover, disposed inside of the staple driver—that is to say, upon the inner flat surface thereof, and is actuated by a spring connection f'' which connects it with the bar f', which spring connection is disposed at the outer vertical edges of the said staple driver and staple former, as shown more clearly in Fig. 5. A latch mechanism f', indicated in dotted lines in Fig. 5, of any suitable or desired character, is employed for automatically locking and unlocking the staple former, in the usual and well understood manner, whereby the said staple former moves downward to form the staple upon the lower end of the loop bar f'', and is then automatically unlocked as soon as it strikes the upper surface of the work, thus permitting the staple driver to then move downward alone to drive the staple. The staple driver has a cam f' that operates the upper end of the loop bar f'', whereby the latter is held in position to form the staple, and then backs away from the path of the driver to permit the latter to drive the staple. In each case the bar f' is held in place by a removable plate f'', which latter is suitably secured to one side edge of the bar e'. It will be seen that the stapler heads F are not disposed exactly below the bar D, so but a little to one side thereof, and are removably secured in place upon the same by the clamping plates f''. The cams e and the bars e' and f' stand squarely face to face and are disposed at right angles to the shaft E and to the bar D. Lower down, however, the staple drivers and formers are given a uniform twist or turn, which makes them all stand obliquely to the line along which the staples are driven. With this arrangement, the stapling heads can be brought very close together, and each stapling head or mechanism is operated by a powerful actuating or driving device. The combined thrust of all the stapler heads is, of course, considerable, and it is for this reason that the strong and rigid construction formed by the shaft E and the bar D and the connecting bars e' is necessary and desirable. With this construction, the thrust of the staplers will not cause any springing or yielding action, even at the outer end of the row of staplers, at least not enough to amount to anything, and each staple will be properly driven.

Each stapler has a feed mechanism G which is mounted upon a bracket g carried by the plate f'', as shown more clearly in Fig. 5. The said feed mechanism may be of any suitable known or approved construction, and is indicated more in detail in Fig. 10. It consists of gear connected feed-rolls g' and g'', and of suitable means for regulating the tension or feeding action thereof in accordance with the requirements of any particular case. Referring to Fig. 3, it will be seen that the said feed mechanisms, which are adapted to feed the wire to the staplers, and which are the same in number as the stapling heads, are all operated by a common shaft H, which extends through the brackets g, the latter serving as bearings for the shaft. The said feed shaft is actuated by a ratchet mechanism I, such as the one shown in Fig. 8, which mechanism is operated by a rod i having its upper end connected with a cam or eccentric device i' on the shaft E. In this way the feed mechanisms are all operated at the same time, and the wire is fed simultaneously to the different stapling heads, the wire for this pur-

pose being carried on reels J which are mounted on long arms or brackets j secured to the clamping plates j¹.

It will be understood that the shaft E is 5 operated by a belt pulley e², or by any other suitable means.

The long clenching bar or mandrel K has its inner end pivoted at k, and is disposed lengthwise of the row of stapler heads, below 10 the same, as shown more clearly in Fig. 1. This bar is adapted to swing up and down at its outer end, and it is adapted to be inserted in the collapsed or flattened box or carton X, as shown in Fig. 5. Said bar is 15 of a length to serve as an anvil for all of the stapling heads, and for this purpose has its upper surface recessed and provided with a set-in piece of steel or other suitable material k', provided with grooves k² that receive 20 the points of the staples. Thus the said bar K is equipped with means for receiving the points of the staples and for clenching the same in any suitable or desired manner, as will be readily understood. 25 The bar K is held normally raised, as shown in Fig. 1, a slight distance above the table C, by the spring k³, which connects its inner end with the post B, whereby one side wall of the box or carton can be readily inserted 30 under the said bar or mandrel K, and the entire box or carton, in a collapsed condition, then moved along said bar or mandrel until the proper position is reached for stapling. When the staples are driven they are all inserted 35 along one longitudinal corner of the box or carton, as shown in Fig. 4, and this is the only stapling that is necessary to fasten the box together. Thus, by one stroke of the multiple stapler-head machine, the 40 entire row of staples is driven, and the box is then taken off from the mandrel or bar, and another one placed thereon.

Gage pieces L and M are secured to the top of the table, at the right-hand side and 45 at the rear thereof, as shown in Fig. 3, whereby the box or carton can be accurately positioned on the table to receive the staples.

The table and the mandrel or clench bar K can be moved up and down by the hand 50 screw e, thus enabling the operator to adjust the machine for different kinds of work.

From the foregoing, it will be seen that I provide a machine in which a number of staples are driven in a row extending along 55 the top of a bar which is inserted in the box or carton, and which rests upon the material of the box or carton during the driving of the staples, whereby all of the staples are driven by one operation of the 60 machine. In this way the machine works very fast, and a large number of boxes or cartons can be stapled in a comparatively short period of time. As the fastener driving units or staplers are all crowded tightly 65 together on the bar D, it follows that the

staples Y are driven close together, thereby forming a practically continuous line of wire stitching.

I do not limit myself to the exact construction shown and described. 70

What I claim as my invention is:

1. A machine for driving fasteners, comprising a bar, a series of fastener driving units strung on said bar, an operating shaft extending through said units, means for holding said bar and shaft in position, means for rotating said shaft, and a support for the work, each unit including a member having a bearing for said shaft, and means for detachably securing said members on said bar, said units being arranged to drive the fasteners obliquely across the line of insertion, each unit having a cam on said shaft, and means for feeding wire to said units in directions oblique to said shaft. 85

2. A machine for driving fasteners, comprising a bar, a series of fastener driving units strung on said bar, an operating shaft extending through said units, means for holding said bar and shaft in position, means for rotating said shaft, and a support for the work, each unit including a member having a bearing for said shaft, and means for detachably securing said members on each bar, said member having a channel, a driver sliding in said channel, a cam on said shaft, and means on said driver to engage said cam, said units being arranged to drive the fasteners obliquely across the line of insertion, each unit having a cam on said shaft, and means for feeding wire to said units in directions oblique to said shaft. 95

3. A machine for driving fasteners, comprising a bar, a series of fastener driving units strung on said bar, an operating shaft extending through said units, means for holding said bar and shaft in position, means for rotating said shaft, and a support for the work, each unit including a member having a bearing for said shaft, and means for detachably securing said members on said bar, said units being arranged to drive the fasteners obliquely across the line of insertion, each unit having a cam on said shaft, and means for feeding wire to said units in directions oblique to said shaft, said means for feeding wire comprising a feed-shaft extending parallel with said operating shaft, means for rotating said operating shaft, and means actuated by said operating shaft to intermittently rotate said feed-shaft. 110

4. A machine for driving fasteners, comprising a bar, a series of fastener driving units strung on said bar, an operating shaft extending through said units, means for holding said bar and shaft in position, means for rotating said shaft, and a support for the work, each unit including a member having a bearing for said shaft, and 125

means for detachably securing said members on said bar, each member having a channel, a driver sliding in said channel, a cam on said shaft, and means on said driver
6 to engage said cam, said units being ar- ranged to drive the fasteners obliquely across the line of insertion, each unit having a cam on said shaft, and means for feeding wire to said units in directions oblique to
10 said shaft, said means for feeding wire comprising a feed-shaft extending parallel with

said operating shaft, means for rotating said operating shaft, and means actuated by said operating shaft to intermittently rotate said feed-shaft. 15

Signed by me at St. Joseph, Michigan,
this 8th day of July, 1910.

EDWARD CRAIG.
